UNITED STATES PATENT OFFICE.

LOANDO B. ESTES, OF NORTH ADAMS, MASSACHUSETTS.

MIRROR-ATTACHING DEVICE.

1,242,335.

Specification of Letters Patent.

Patented Oct. 9, 1917.

Application filed November 23, 1916. Serial No. 133,021.

To all whom it may concern:

Be it known that I, LOANDO B. ESTES, a citizen of the United States, residing at North Adams, in the county of Berkshire and State of Massachusetts, have invented certain new and useful Improvements in Mirror-Adjusting Devices; and I do declare the following to be a full, clear, and exact description of the invention, such as will enable others skilled in the art to which it appertains to make and use the same.

This invention relates to improvements in attachments for dressers, bureaus, chiffoniers and other articles of furniture having mirrors mounted thereon.

One of the objects of the invention is to provide a very simply constructed device for holding a mirror at any angle desired.

An additional object is to provide a means for readily actuating the mirror adjusting device.

With these general objects in view the invention resides in certain novel features of construction, combination and arrangement 25 of parts which will be herein more particularly described and claimed.

In the accompanying drawing:

Figure 1 represents a front elevation of a bureau equipped with mirror adjusting 30 means constructed in accordance with my invention;

Fig. 2 is a rear elevation of the parts shown in Fig. 1;

Fig. 3 is a side elevation of the invention applied to the mirror;

Fig. 4 is a horizontal section on the plane of the line 4—4 of Fig. 2; and,

Fig. 5 is a detail vertical section on the line 5—5 of Fig. 2.

It will be seen from the accompanying drawing that the invention may be readily applied to practically any article of furniture having a mirror thereon mounted to swing between horizontal pivots. The attachment is applied to a bureau B having the usual upright supports or standards S between which the mirror M is pivoted. The pivot pins 1 which extend through the upper ends of the standards S are preferably in a horizontal plane and are disposed in sockets substantially in the center of the sides of the mirror.

In equipping the bureau with my invention it is first necessary to form an opening 2 transversely through the body of the piece of furniture from front to rear thereof and

adjacent one corner, in this instance it being formed through the upper right hand corner adjacent the side edge. In this opening is disposed a shaft 3, the ends thereof 60 projecting beyond the front and rear of the bureau, the front end being provided with an operating knob or handle 4 while the rear end has a crank in the form of a plate 5 fixed thereto. A wear plate 6 is disposed 65 between the knob 4 and the front of the bureau for a purpose which will later be more particularly described.

The rear face of the frame of the mirror M carries an ear 7, this ear being in the 70 form of a right angular plate, one arm of which is attached to the said frame and the other has an opening therethrough. This ear 7 is secured to the mirror frame adjacent one of the pivots on the side nearest 75 the opening 2.

A link 8 connects the crank 5 with the ear 7, said link having an eye 9 for engagement with the ear 7, while its lower end is bent laterally outward as shown at 10. The 80 lower end portion of the link is curved so as to dispose the extreme lower end in engagement with the back of the bureau and is held in this position by being disposed between said back and the plate forming the 85 crank 5. This crank has an opening 11 adjacent one end to receive the outwardly extending end 10 of the link, said crank being slightly offset to allow the link to be disposed between it and the bureau, thus disposing the end of the crank in engagement 90 with the end of the link. The latter will be reliably held in engagement with the former at all times, yet it may be quickly disengaged when it is desired to remove the 95 mirror, as for instance when the bureau is to be transported from one house to another.

Furthermore the disposition of the end of the link in engagement with the back of the bureau permits the mirror to be held at any 100 desired angle without danger of its moving back to the vertical position, in other words, there is ordinarily sufficient frictional engagement between the link and the bureau to hold the crank until manually moved by 105 operation of the knob 4. In case, however, the friction between these parts is insufficient a wear plate 6 having a roughened or serrated outer face may be disposed behind handle or knob 4 and secured to the bureau. 110

The movement of the crank 5 is preferably limited in both directions by pins or

studs 12 which projects from the back of the mirror. The upper pin limits the upward movement of the crank and prevents the lower end of the mirror swinging rearwardly beyond a predetermined point, and the lower pin limits the outward movement of the bottom of the mirror.

From the foregoing description taken in connection with the accompanying drawing 10 it is obvious that I have invented an extremely simple device whereby a pivoted mirror on any article of furniture may be adjusted to various angles and held in these positions.

15 I claim:

The combination with an article of furniture having an opening adjacent one side edge and extending therethrough from front

to rear, of a mirror mounted on said article to swing between horizontal pivots, a shaft 20 disposed in said opening and projecting beyond the ends thereof, a crank on the rear end of said shaft, one end of the crank having an aperture, an ear projecting from the rear of the mirror adjacent one of its pivots, 25 and a link loosely attached at one end of said ear, its other end being bent laterally and disposed in the aperture in said crank.

In testimony whereof I have hereunto set my hand in the presence of two subscribing 30 witnesses.

LOANDO B. ESTES.

Witnesses:
